UNITED STATES PATENT OFFICE.

ISAAC O. DUNCAN, OF NASHVILLE, TENNESSEE.

BABY JUMPER.

Application filed August 29, 1924. Serial No. 734,949.

This invention has as its object to provide an improved baby jumper embodying means for weighing a baby using the jumper so that the state of health of the baby may be 5 informatively watched by noting the weight of the baby from time to time.

In the accompanying drawings:

Figure 1 is a perspective view of my improved baby jumper.

10 Figure 2 is a top plan view of the device.

Figure 3 is a rear elevation of the device.

In carrying the invention into effect, I employ a frame which is composed of a pair of slidably connected yokes 10 and 11 respectively. Each of these yokes is preferably formed from a length of material bent into substantially U-shape to provide a pair of parallel side rods 12 joined by a connecting portion looped to provide an eye 13

20 while at the ends of the rods are formed lateral loops 14', the loops of each yoke slidably accommodating the rods of the other yoke for connecting the yokes with each other. Associated with the frame is a spring 14 pro-

25 vided at its upper end with a hook 15 engaged through the eye 13 of the yoke 10 while at its lower end the spring is provided with a similar hook 16 engaged through the eye of the yoke 11. The spring will thus

30 normally hold the yokes at the limit of their inward sliding movement upon each other. Fixed to the yoke 10 of the frame is a face plate 17 overlying the spring 14. This face plate is preferably of sheet metal and is con-

35 cavo convex in cross section so as to clear the spring. Formed on the plate at the upper corners thereof are rearwardly directed lugs 18 which are bent about the connecting portion 10 between the side rods 12 of said yoke.

40 Another pair of the lugs 18 located at the lower corners of the plate is similarly secured to the side rods of the yoke. Thus the face plate is rigidly fixed to the yoke 10 so as not to interfere with the sliding movement

45 of the yokes 10 and 11 upon each other. At its outer side, the face plate 17 is calibrated at one longitudinal edge thereof, as indicated at 19, to read in terms of pounds, and fractions thereof if desired, and fixed to the

50 adjacent side rod of the yoke 11 near its upper end is, as particularly shown in Figure 3 of the drawings, an indicator 20, bent to overhang the face plate to cooperate with the scale thereon. To enhance the attractiveness of the device, the face plate 17 may, as suggested in Figure 1, carry the picture

of a baby while, as a matter of convenience, the face plate is also preferably provided, as indicated at 21, with a tabulation of the average weight of a normal infant at different 60 ages.

Suspended by the spring 14 is a sling 22. This sling may be of any approved character and in the present instance the sling is shown as provided with a fabric seat 23 having 65 openings to receive the legs of an infant while at its upper end the sling is provided with a hook 24 removably engaged through the eye 13 of the yoke 11. In use, the device is, of course, attached to any convenient overhead structure and, in the present instance, I have shown the use of a hook 25 with which the eye 13 of the yoke 10 is engaged.

As will now be seen in view of the foregoing, a baby sitting in the seat 23 of the sling 22 will be yieldably supported by the spring 14 so that the device will thus ordinarily serve all the purposes of a conventional baby jumper. However, the device 70 will, as will also now be appreciated, provide, in addition, a means whereby the weight of the baby may be conveniently noted from time to time. The spring 14 will, of course, be stretched under the weight of the 75 baby so that the yoke 11 will be shifted downwardly upon the yoke 10 for moving the indicator 20 to a given reading of the scale 19 and thus register the weight of the 80 baby. Accordingly, the increase or decrease 85 in weight of the baby may be conveniently watched carefully, as is necessary with infants in order that the parent may be properly informed as to the state of health of the 90 baby. The attachment embodying the in- 95 vention presents another advantage, namely, that as the baby increases in weight and becomes more energetic, its efforts to produce the bouncing motion common to devices of this class will naturally cause the indicator 100 to move to a lower point upon the scale at each downward movement of the swing and the increase in such movement may be watched with interest by the parents.

Having thus described the invention, what 105 I claim is:

1. In a device of the character specified, a frame comprising similar members inversely disposed and slidably related, each of the members including a yoke having a medial eye and parallel side rods terminating in lateral loops, the loops of one member en-

- gaging the rods of the companion member, a coil spring arranged between the rods of the members and engaged at its ends with the eyes of the respective yokes, a plate covering a side of the frame and the spring and attached to one of the members and provided with scale graduations, and an indicator movable over the plate and carried by the other member.
- 10 2. In a device of the character specified, a frame comprising similar members inversely disposed and slidably related, each of the members including a yoke having a medial eye and parallel side rods terminating in lateral loops, the loops of one member engag-

ing the rods of the companion member, a coil spring arranged between the rods of the members and engaged at its ends with the eyes of the respective yokes, a plate covering a side of the frame and the spring and provided at opposite ends with lugs engaged about elements of one of the members and provided with scale graduations, and an indicator carried by the other member and engaged about an edge portion of the plate and adapted to coact with the scale graduations thereof.

In testimony whereof I affix my signature.

ISAAC O. DUNCAN. [L. S.]
